Primary Examiner — Daniel J Domino(74) *Attorney, Agent, or Firm* — BakerHostetler**(57) CLAIM**

The ornamental design for a display screen with graphical user interface, as shown and described.

DESCRIPTIONFIG. 1 is a front view of a display screen with graphical user interface showing my new design; and,
FIG. 2 is an alternate front view thereof.

The outermost broken line perimeter illustrates a display screen and forms no part of the claimed design. The remaining broken lines illustrate portions of a graphical user interface which form no part of the claimed design.
